UNITED STATES PATENT OFFICE.

CLYDE F. COLLIER, OF LAKEVILLE, OHIO, ASSIGNOR OF ONE-HALF TO JOHN C. LAKE,
OF BIG FRAIRIE, OHIO.

RURAL-MAIL-DELIVERY SIGNALING APPARATUS.

1,131,211.

Specification of Letters Patent.

Patented Mar. 9, 1915.

Application filed January 4, 1912. Serial No. 669,402.

To all whom it may concern:

Be it known that I, CLYDE F. COLLIER, a citizen of the United States, and a resident of Lakeville, in the county of Holmes and 5 State of Ohio, have invented certain new and useful Improvements in Rural-Mail-Delivery Signaling Apparatus, of which the following is a specification, reference being had to the accompanying drawings.

10 This invention relates to improvements in rural mail delivery signaling apparatus.

One object of the invention is to provide a semaphore signal, adapted to be employed in connection with the delivery and collection of rural mail, whereby the carrier may inform owners of rural mail boxes who may live some little distance therefrom, when he has placed mail matter in their box and whereby the owners of the box may inform 20 the carrier when there is mail in the box for collection, thus saving a great deal of time which is usually lost by both owner and carrier in making unnecessary trips to the mail box, when there is no mail therein.

25 The invention further resides in the provision of a simple and inexpensive semaphore signal apparatus of the character described, which may be readily operated, and may be seen from a considerable distance and in the provision of an alarm to be used in connection with the visible signal, and actuated by the operating mechanism of the same to call the attention of the owners of the mail box to the fact that mail has been placed therein, particularly when for any reason the semaphore signal cannot be seen from the owner's house.

30 With these and other objects in view, the invention consists of certain novel features of construction, combination and arrangement of parts as will be more fully described and claimed, it being further understood that changes in the specific structure shown and described may be made 45 within the scope of the claims without departing from the spirit of the invention.

In the accompanying drawings, forming a part of this specification and in which like numerals of reference indicate similar parts in the several views: Figure 1 is a side view of my improved signal, showing the signal arm and target in a lowered position indicating that the mail box is empty. Fig. 2 is a similar view showing the target raised to its highest position in full lines,

which indicates that there is mail in the box for the owner. Fig. 3 is an edge view of the target operating and locking mechanism shown in Figs. 1 and 2.

In carrying out my invention, I provide 60 a pole or post 1, which may be of any desired length or height, and which has its lower end anchored or secured in the ground in any suitable manner. To the pole and preferably near its upper end is secured a 65 target attaching plate 2, having thereon near one of its upper corners a stop lug 3. Pivoted on the plate 2 is a target arm 4, having on one end a signal target 5, which may be of any shape or design and colored 70 in any desired manner. The opposite or shorter end of the arm 4 is curved downwardly as shown, and has formed therein an eye 6.

To the pole or post 1 at a point within 75 reach from the ground is secured a lever supporting plate 7, which is bent around and embraces the pole at one end and has its opposite end rounded and projecting beyond the pole as shown. On the rounded 80 end of the plate are arranged a plurality of ratchet teeth or lugs 8, three of which are preferably provided. Pivottally connected at its inner end to the plate 7 is a target operating lever 9, the outer end of which 85 projects beyond the rounded end of the plate and has formed thereon a handle 10.

The pivot bolt 11, of the lever extends beyond the outer side of the same and has thereon a nut 11^a, between which and the 90 lever is arranged a coil spring 12, whereby the lever is held in yielding engagement with the outer side of the plate and with the teeth or lugs 8. The yielding engagement of the lever with the plate also permits the lever to be sprung over the teeth or lugs when shifted from one to the other in operating the signal. The lever 9 is connected to the eye 6 in the shorter end of the target arm by an operating rod 13, whereby 100 the movement of the lever is imparted to the target arm and target, and the latter adjusted to the desired position.

Secured to the pole or post 1 preferably below the lever supporting plate is a mail box supporting bracket 14, to which is fastened the mail box 15. The box 15 may be of any suitable construction and is preferably provided with a hinged cover 16 adapted to be held down in closed position by a finger 110

17, on the target operating lever 9, when the latter is swung down to elevate the target to the position for indicating that mail has been placed in the box. The finger 17 when 5 thus engaged with the cover of the box will prevent the same from being blown or otherwise casually opened while there is mail in the box.

At a suitable position on the pole is preferably arranged a sign board 18, on which may be placed the name, address or route number of the owner of the box, or any other information which it may be desired to display.

15 In the operation of the device, when the carrier has placed mail in the box, he swings the lever 9 downwardly into engagement with the lower tooth on the plate 7 which operation will lift or swing the target arm 20 and target upwardly to the position shown in Fig. 2 of the drawings, thus indicating to the owners of the box that mail has been placed therein. When mail is removed from the box, the lever is released from the lower 25 tooth and swung upwardly into engagement with the upper tooth, thus lowering the target to the position shown in Fig. 1, in which position the same remains until more mail is placed in the box. In thus swinging 30 the target to its raised and lowered positions, the target arm will come into engagement with the stop lug 3 on the plate 2, which will limit the movement of the arm and hold the same in position.

35 When it is desired to signal to the carrier that mail has been placed in the box for collection, the lever is swung down into engagement with the middle or intermediate tooth on the plate 7, thus raising the target only 40 half way up.

In connection with my signaling device I employ an electric alarm mechanism comprising an electric circuit 32, in which is arranged a bell 33, and a battery 34. One terminal of the circuit is connected with the 45 fixed member 35, of a switch secured to the plate 7 of the target operating lever, and the other terminal of the circuit is connected to the movable member 36, of the switch, 50 said member 36 being in the form of a spring arm having on its end a contact knob 37, adapted to be engaged by the lever 9, when the latter is swung downwardly to

operate the target, and to be pressed down by the arm into engagement with the fixed 55 members of the switch, thereby completing the electric circuit and sounding the alarm.

From the foregoing description taken in connection with the drawings, the construction and operation of the invention will be 60 readily understood without requiring a more extended explanation.

Various changes in the form, proportion and the minor details of construction may be resorted to without departing from the 65 principle or sacrificing any of the advantages of the invention as claimed.

Having thus described my said invention, what I claim as new and desire to secure by United States Letters Patent is:

70 1. In a rural mail delivery signaling apparatus, a supporting post, a signal target pivotally mounted thereon, means whereby said target is elevated, means to support the same at different angles, a mail box secured to said post, and means carried by said target operating mechanism to engage and hold down the cover of the box when the target is in a raised position.

75 2. In a rural mail delivery signaling apparatus, a supporting post, a signal target arm pivotally mounted thereon, a signal target arranged on said arm, a lever supporting plate secured to the post, ratchet teeth arranged on said plate, a target operating lever pivoted on said plate, an operating rod to connect said lever with said target arm whereby when the lever is swung around into engagement with said teeth, 80 said arm and target will be held at different angles, thereby forming different signals, a mail box secured to said post, a finger carried by said lever to engage and hold the cover of the box in closed position, an electric alarm circuit, an alarm arranged 85 therein and a circuit closer arranged on said lever supporting plate and adapted to be engaged and closed by said lever when the latter is depressed to raise the target.

90 95 95 In testimony whereof I affix my signature, 100 in presence of two witnesses.

CLYDE F. COLLIER.
